UNITED STATES PATENT OFFICE.

HENRY L. SCOTT, OF PROVIDENCE, RHODE ISLAND.

TESTING-MACHINE.

1,372,093.

Specification of Letters Patent. Patented Mar. 22, 1921.

Application filed April 21, 1917. Serial No. 163,553.

To all whom it may concern:

Be it known that I, HENRY L. SCOTT, a citizen of the United States, and resident of the city of Providence, in the county of Providence and State of Rhode Island, have invented certain new and useful Improvements in Testing-Machines, of which the following is a specification.

This invention relates to switch operating mechanism for testing machines for automatically controlling the action of the driving motor, and the object of this invention is to provide in such a machine simple and effective means for reversing the direction 15 of travel of the tension mechanism at the end of its operating stroke.

The invention further consists in providing means for automatically stopping the motor if desired when the tension mechanism has completed a downward stroke and returned to the starting point.

With these and other objects in view, the invention consists of certain novel features of construction, as will be more fully described, and particularly pointed out in the appended claims.

In the accompanying drawings:

Fig. 1—is a side elevation of the clamp operating mechanism.

Fig. 2—is an end view on a larger scale sectioned on line 2—2 of Fig. 1 showing the arrangement of mechanism through which the electric switch is operated.

Fig. 3—is a face view of the switch having start, reverse and stop terminals.

Fig. 4—is a face view of a switch having start and reverse terminals only.

Fig. 5—is an outline of a knife switch which may be inserted in the main line for starting the motor.

Referring to the drawings, 10 designates the screw shaft member which is connected to the lower clamp 11 and through which tension is applied to the goods 12. This 45 screw threaded shaft is provided with an operating nut 13 working between the end bearings 14 and 15. This nut is shown as being provided with a worm gear, which is rotated by means of a worm 17 mounted on the shaft 18 on the electric motor 19 whereby the action of this motor causes the nut to rotate and so provide an endwise motion to the screw.

In order to control the action of this motor, I have provided an electric switch 20, a simple form of which is shown as being

connected to the motor through the wires 21. This switch is provided with a switch bar 22 adapted to be rotated through its center spindle 23 to complete the circuit through the various contact points. For instance when the bar is in the position shown in Fig. 3 the circuit is broken to stop the motor; when moved to engage contact 25 it completes the circuit to the motor and rotates the same in one direction; when moved to contact 26 it reverses the current through the motor and drives the motor in the opposite direction, and when moved to contact 27 the circuit is again broken.

This switch may be operated by hand through the handle 28 to the first position and then be operated automatically through the action of the operating mechanism to the other two positions or it may be operated entirely by hand if desired.

To accomplish this automatic action in a simple and practical way, I have provided two endwise slidable racks 29 and 30 movably mounted in the frame 31, and have provided a short shaft 32, one end of which is connected to the switch operating shaft 23 and on this short shaft is mounted a gear 33 which engages rack 30 and gear 34 which mesh with the pinion 35, which in turn engages rack 29. These two gears 34 and 33 are connected together to rotate freely on shaft 32, gear 33 being mounted upon and fixed to the hub of gear 34.

A ratchet wheel 36 is connected by a set 90 screw 37 to this short shaft 32 and is engaged by a pawl 38 mounted on the gear 33, whereby a downward movement of rack 29 acting through its pinion and gear serves to rotate the switch in a clock-wise direction 95 through the said pawl and ratchet and it will be also seen that by a direct connection between the rack 30 and the gear 33 that an upward movement of this rack also moves the switch in a clock-wise direction through the same pawl and ratchet wheel but at a greater rate of speed, and that a movement of one rack moves the other in the opposite direction.

The operation of the device is as follows:—To start the motor it is necessary to throw the switch by hand from point 27 to point 25. The motor is thus energized and the tension screw moved downward until the arm 39 which is fixed thereon engages and moves the rack 29 in the same direction. This action throws the switch from contact

25 to contact 26, thereby reversing the direction of the current and the direction of rotation of the motor, which action serves to return the screw to its raised or normal position. As soon as released the racks are 5 both returned to normal by spring 41 that is rack 24 to its raised and rack 30 to its lower position, but owing to the difference in the gearing they travel at different speeds 10 and each with a different length of stroke, the action of both, however, upon the switch is to advance it one step at each action.

When the screw approaches its up position 15 its lower arm 40 engages the rack 30 which has now been positioned to receive it and through the mechanism above described rotates the switch onto the point 27, which automatically stops further action of the motor until again started by the hand of the 20 operator.

I have shown and described a switch 25 whereby its movement by the hand of the operator starts the motor and after the motor has completed a cycle, which is a movement of the screw first downward and then upward, the motor is automatically stopped, but in some cases such as applying what is known as the "fatigue" test to a strip of 30 elastic material, which is that of seeing how many times this material can be stretched a given amount before breaking, it is found desirable to provide a switch mechanism which will cause the motor to automatically reverse at the upper, as well as at the lower 35 end of its stroke, and so continue to reciprocate until stopped by the hand of the operator.

To accomplish this, I have provided a 40 switch such as that illustrated in Fig. 4 which has two contacts 42 and 43, when the switch bar 22 is on 42 the motor is caused to run in one direction and when on 43 the motor is caused to run in the opposite direction, the circuit being completed and broken 45 in the main line by means of a hand switch such as illustrated in Fig. 5.

The foregoing description is, of course,

directed solely toward the construction illustrated, but the device is susceptible of modifications, the invention not being limited in 50 any other way than by the terms of the appended claims.

I claim:

1. In a testing machine, a screw through 55 which tension is applied for the test, an operating nut on said screw, an electric motor mounted to rotate said nut to impart an endwise motion to said screw, an electric switch, and a switch operating member actuated by the movement of said screw at the 60 end of one stroke thereof to throw said switch to at once reverse the action of said motor and at the end of its opposite stroke to stop said motor.

2. In a testing machine, a screw through 65 which tension is applied for the test, an electric motor for operating said screw, and means including pawl and ratchet mechanism arranged to be actuated by the movement of said screw for operating said switch 70 to control the action of said motor.

3. In a testing machine, a screw through 75 which tension is applied for the test, an electric motor for operating the screw, an electric switch, and means including a pair of reciprocating racks actuated by the movement of said screw for operating said switch to control the action of said motor.

4. In a testing machine, a screw through 80 which tension is applied to the goods, an electric motor for operating said screw, an electric switch, pawl and ratchet mechanism through which said switch is rotated, a pair of reciprocating racks through which said 85 ratchet is operated, and means on said screw for engaging and moving said racks at opposite ends of its strokes whereby the operation of said motor is controlled.

In testimony whereof I affix my signature in presence of a witness.

HENRY L. SCOTT.

Witness:

HOWARD E. BARLOW.
